W. E. ELLIOTT,
PACKAGE OF SNAP FASTENERS,
APPLICATION FILED MAR. 28, 1916.

1,289,136.

Patented Dec. 31, 1918.

UNITED STATES PATENT OFFICE.

WILLIAM E. ELLIOTT, OF GRAND RAPIDS, MICHIGAN, ASSIGNOR TO AMERICAN BUTTON & FASTENER COMPANY, A CORPORATION OF MAINE.

PACKAGE OF SNAP-FASTENERS.

1,289,136.

Specification of Letters Patent. Patented Dec. 31, 1918.

Application filed March 28, 1916. Serial No. 87,214.

To all whom it may concern:

Be it known that I, WILLIAM E. ELLIOTT, a citizen of the United States of America, residing at Grand Rapids, in the county of 5 Kent and State of Michigan, have invented certain new and useful Improvements in Packages of Snap-Fasteners; and I do hereby declare the following to be a full, clear, and exact description of the invention, such 10 as will enable others skilled in the art to which it appertains to make and use the same.

This invention relates to packages of snap fasteners of the type, comprising two separable parts, which is commonly used upon 15 articles of wearing apparel.

One object of the invention is to devise a package of snap fasteners mounted upon a narrow strip of flexible material in such a 20 way that a large number of fasteners are positioned with their parts in alinement upon opposite sides of the mounting strip and thus may be carried to an attaching machine wherein the parts of the fasteners 25 may be consecutively stripped from the mounting strip with the operation of the machine and attached to articles of wearing apparel.

In another aspect, the invention provides 30 a novel package of a series of snap fasteners occupying a small space and adapted to be transferred in this form to an attaching machine.

A feature of the invention relates to the 35 provision of a mounting strip for snap fasteners arranged to retain one element of the fastener upon the strip by the co-action of the strip with said part of the fastener and to retain the other element of the fastener 40 upon the strip by its co-action with the first part when disposed upon the opposite side of the strip from the first-mentioned part and secured thereto in the usual fashion.

The invention will be readily understood 45 from a consideration of the following specification in which is described one precise embodiment thereof with reference to the accompanying drawings, in which—

Figure 1 shows a package containing a 50 large number of snap fasteners mounted consecutively upon a narrow mounting strip.

Fig. 2 is a vertical section of one type of fastener which may be used; and

Fig. 3 is a perspective view somewhat enlarged of a portion of the mounting strip

having a number of fasteners secured theron.

Like reference characters refer to like parts throughout the several views of the drawing.

The mount on which the fasteners are secured consists, preferably, of a thin, narrow, elongated strip of paper 1, which is flexible and may be easily rolled into small compass. This strip of paper is provided 65 with substantially equally spaced perforations 9 and preferably one or more radial slits 10 are formed around these perforations in order to allow the insertion of a member having a slightly greater diameter than the 70 normal diameter of the opening without tearing the paper. The snap fasteners used are of any preferred type. I have shown one type in the drawing though it is to be understood that the specific construction of 75 the fastener used is not material to this invention. The fastener illustrated consists of two separable parts, one of which includes a base 2 having projecting centrally therefrom a rounded head 3 connected to the base 80 by a neck portion 8 of reduced diameter. The perforations are preferably formed of such a size that their diameter is slightly less than the diameter of the rounded head 3 of the fasteners. On account of the radial slits 85 provided adjacent the perforations, however, this enlarged head may be readily pushed through the opening in the strip of paper, whereupon the paper will spring back into place and engage the reduced neck portion 90 thereby to hold this element of the fastener in position upon the strip. The opposite member of the fastener consists of a cup-like body 4 of circular outline, a hole being formed at its center for the passage of the 95 head 3 over which hole an inclosing member 5 is positioned into which the head may enter. The member 5 is slotted at either side to permit the passage of arms 6 formed at the extremities of a spring 7 of wire and 100 received within the member 4 of the fastener, these arms engaging against the reduced neck 8 below the head 3 and yieldingly holding the parts of the fastener together.

In mounting fasteners of this or any other similar type on the strip the head 3 is forced through the strip, the base 2 lying at one side of the strip while the head 3 is on the opposite side and in position to receive the other 110

member of the fastener. It should be noted that this element of the fastener is retained in position upon the strip, as previously described, by the co-action of the paper with the reduced neck portion of the fastener and may, therefore, be left in this relation until it becomes desirable to attach the other element of the fastener. The other element is then attached to the strip by causing it to engage the upstanding head in its customary fashion and is retained upon the strip only by virtue of such engagement. A large number of these fasteners are attached in this manner consecutively on the strip as indicated in Fig. 3 and the strip with the attached fasteners is wound into a package like a belt with the heads of the fasteners projecting toward the inside of the roll, the resulting package occupying comparatively little space and being easily unwound as it is fed to a machine which uses fasteners of this character, it being understood that as the strip goes to the machine the fastener parts are separated from each other and from the strip and guided into suitable raceways which carry them to the articles to which they are to be attached without destroying the mounting strip.

I claim:—

1. A package of two-part snap fasteners arranged in a series, comprising a narrow, thin, elongated strip of paper, and a plurality of snap fasteners each comprising two elements, one of the elements being constructed with a base and an upstanding head having an enlarged portion connected to said base by a neck portion of lesser size, the head portions of said elements being passed through said strip in consecutive spaced relation, said strip being provided

with radial slits surrounding the point at which the head portions are passed through the strip whereby these elements may be inserted in the strip without danger of tearing the same and are retained therein by engagement of the strip with the neck of the fastener, the other elements of said fasteners being arranged to pass over the head portions of the first named elements and resiliently engage the neck portions, said strip with the fasteners mounted therein being wound in a roll.

2. A package of the character described, comprising a narrow, thin, elongated strip of paper provided with a series of substantially equally spaced perforations, radial slits in said paper around said perforations, a plurality of snap fasteners each comprising two elements, one of the elements being constructed with a base and an upstanding head having an enlarged portion and a neck portion of lesser size and the other element being arranged to pass over the head portion of said fastener and resiliently engage its neck portion, said perforations being of slightly less diameter than the diameter of the enlarged portion of the head of the fasteners, said first-named elements having their head portions pushed through the perforations in said strip of paper wherein they are retained by the paper, said other elements being engaged with the projecting head portions of the fasteners whereby they are held upon the strip, and said strip with the fasteners mounted thereon being wound in a roll with the heads projecting toward the inside of the roll.

In testimony whereof I affix my signature.

WILLIAM E. ELLIOTT.
